UNITED STATES PATENT OFFICE.

JACOB M. CRIPE, OF DES MOINES, IOWA.

AIRSHIP.

1,289,402.

Specification of Letters Patent. Patented Dec. 31, 1918.

Application filed October 6, 1917. Serial No. 195,092.

To all whom it may concern:

Be it known that I, JACOB M. CRIPE, a citizen of the United States, residing at Des Moines, in the county of Polk and State of Iowa, have invented a new and useful Airship, of which the following is a specification.

This invention relates to airships, one of its objects being to combine with an aeroplane, all of the advantageous features of an aerostat or lighter than air machine.

It is a well known fact that aeroplanes are dependent upon momentum in order to remain at a desired elevation and, consequently, in the event of failure of any important parts of the machine, the machine will drop to the ground. A lighter than air machine, on the contrary, will be maintained at a desired elevation whether or not in motion but is objectionable because of its unwieldy nature.

One of the objects of the present invention is to utilize an aeroplane in which the sustaining planes constitute gas holders, the machine also including a propelling screw likewise constituting a gas container so that the machine will not only have the self sustaining characteristics of a lighter than air machine, but can also be manipulated easily and efficiently as the usual aeroplane.

With the foregoing and other objects in view, which will appear as the description proceeds the invention resides in the combination and arrangement of parts and in the details of construction hereinafter described and claimed it being understood that changes in the precise embodiment of the invention can be made within the scope of what is claimed without departing from the spirit of the invention.

In the accompanying drawings the preferred form of the invention has been shown.

In said drawings:-

Figure 1 is a side elevation of a machine embodying the present improvements.

Fig. 2 is a plan view thereof.

Fig. 3 is a front elevation.

Fig. 4 is an enlarged view partly in transverse section and partly in elevation of a portion of the propelling screw.

Fig. 5 is an enlarged transverse section through a portion of one of the sustaining planes.

Referring to the figures by characters of reference 1 designates a sustaining plane of

any desired proportion, the same being preferably made of thin metal, preferably aluminum and subdivided into a number of small compartments as indicated particularly in Fig. 5. These compartments are 60 non-communicating and located in each compartment is an expansible gas container 2 in communication with an inlet port 3 which can be supplied with air from any suitable source through a supply tube 4. 65 A check valve 5 may be provided, if desired, for preventing the escape of gas from the inflated container. Under normal conditions each container occupies a comparatively small space in its compartment in 70 the sustaining plane but, when gas is directed into the container, said container will be expanded so as to fill every portion of the compartment in which it is located. In Fig. 5 two of the gas containers have been 75 shown inflated while a third container has been shown deflated.

In the machine illustrated three sustaining planes have been shown, the plane 1 being located above another corresponding 80 plane 6 which is similar in construction thereto there being a third plane 7 located some distance below the plane 6 but of the same proportions as the planes 1 and 6 and, like said plane, provided with interior compartments in which are located inflatable gas containers. The several planes are connected at desired points by struts 8 and all of the planes preferably occupy parallel planes. The distance between the planes 85 6 and 7 is much greater than the distance between the planes 1 and 6 and extending longitudinally of the machine between the planes 6 and 7 is a tubular shaft 9 the middle portion of which is extended through 90 a car 10 preferably located midway between the ends of the machine. In the machine illustrated this car is divided into a lower or passenger holding compartment 11 and an upper or baggage compartment 12, the shaft 100 9 being extended between the two compartments. The car is fixed to certain of the struts fastened to the planes so as to be fixed relative to the planes.

Mounted on those portions of the shaft 9 105 extending beyond the ends of the car 10 are propeller screws 13. Each convolution of each of these screws is made up of a series of hollow segments 14 fastened together in any manner desired and provided, at their 110

- inner ends, with ports 15 opening into the shaft 9 or into gas conductors 16 arranged in the shaft. Located in each of the segments 14 is an expandible gas container 17 into which the ports 15 open and a check valve 18 may, if desired, be provided adjacent each port to prevent the escape of gas by way of the port from the container 17.
- 10 It will be understood of course that when the gas containers 17 are inflated they will completely fill their respective segments 14 and the machine is so proportioned that when all of the gas containers within the 15 propelling screws and within the sustaining planes are inflated the machine, with its load, will leave the ground. Any suitable means, not shown, may be provided whereby the various gas containers can be 20 separately inflated with gas produced by a generator located at any desired point in the machine. Thus while the machine is on the ground only a few of the gas containers can be inflated but, in beginning a flight, gas 25 may be directed into a sufficient number of containers to neutralize the weight of the machine and cause the machine to rise from the ground. The rotation of the screws will cause the machine to travel forwardly.
- 30 A rudder 19 is mounted at the front end of the machine and can be manipulated in any suitable manner to cause the machine to ascend or descend or to turn to the right or toward the left.
- 35 What is claimed is:—
1. An airship including superposed parallel sustaining planes, each of said planes being hollow and subdivided into a plurality of non-communicating compartments, 40 an expandible gas container within each compartment, and propelling means interposed between and extending longitudinally of the sustaining planes, said means including a screw having each convolution made 45 up of a plurality of hollow segments, and

an expandible gas container within each segment.

2. An airship including superposed sustaining planes, each plane being hollow and subdivided into a plurality of compartments, a propelling screw extending longitudinally of the machine and interposed between the planes, the convolutions of the screw being hollow and subdivided into separate non-communicating compartments, 50 and expandible gas containers within all of the compartments in the plane and screw.

3. An airship including superposed hollow sustaining planes, each plane including a plurality of non-communicating compartments, a shaft extending longitudinally between the planes, spaced propelling screws upon the shaft, the convolutions of each screw being hollow and having separate non-communicating compartments therein, 60 and expandible gas containers within the respective compartments in the planes and screws.

4. An airship including superposed hollow sustaining planes, each plane including a plurality of non-communicating compartments, a shaft extending longitudinally between the planes, spaced propelling screws upon the shaft, the convolutions of each screw being hollow and having separate 70 non-communicating compartments therein, and expandible gas containers within the respective compartments in the planes and screws, and a car interposed between the planes and the screws and fixed relative to 75 the planes, said shaft being extended through the car.

In testimony that I claim the foregoing as my own, I have hereto affixed my signature in the presence of two witnesses.

JACOB M. CRIPE.
